ELBRIDGE G. W. BARTLETT, OF PROVIDENCE, RHODE ISLAND.

Letters Patent No. 103,282, dated May 24, 1870.

IMPROVED CLOTHES-WRINGER.

The Schedule referred to in these Letters Patent and making part of the same.

To all whom it may concern:

Be it known that I, ELBRIDGE G. W. BARTLETT, of the city and county of Providence, in the State of Rhode Island, have invented a new and useful Improvement in Clothes-Wringers; and I do hereby declare that the following specification, taken in connection with the drawings making a part of the same, is a full, clear, and exact description thereof.

Figure 1 is a front elevation of a clothes-wringer with my improvement.

Figure 2 is a side view of the driving-gear for the squeezing-rollers and the clearing-roller.

Figure 3 is an improved clamp used with such machines.

A machine for wringing water from clothes, as is well known, consists in general of a pair of rollers, elastic and impervious to water, placed parallel with each other, and having their axle-bearings in upright standards, which latter are tied together by cross-bars.

One of such rollers is driven by a crank attached to its shaft, and its fellow is made to revolve either by the friction of the clothes in passing between the rollers upon its surface, or by a cog-wheel upon its shaft, the teeth of which engage with a cog-wheel upon the crank-shaft of the turning roller.

Such rollers are also so arranged that their surfaces can be separated for a limited distance, to allow the passage of thick folds of cloth, and the yielding pressure of springs, made adjustable by pressure-screws, is also applied to the upper roller, to cause the surfaces of the rollers to squeeze the clothes.

The apparatus is also adapted for attachment, at pleasure, to the side of a wash-tub.

Except in the particulars hereinafter specified, the machine shown in the drawings corresponds with the well-known machine above described.

My first improvement consists in the employment of a friction driving-gear, to operate the squeezing-rollers, in place of toothed wheels heretofore employed, the advantage of which is that the rollers can be allowed to separate from each other much farther for the passage of thick folds of cloth, without throwing the driving-gear out of engagement, than, in machines employing cog-wheels, would be practicable.

The upper roller A has a disk-plate, B, keyed to its shaft.

The lower roller C has another disk-plate, D, attached to its shaft by a feather or other means which allow it to be moved along the shaft, but not to revolve around it.

A clamp-nut, E, and also, if preferred, a spring, are placed back of this plate, upon turning which nut the degree of friction which shall exist between the inner face of D and the outer face of B can be increased or diminished, the arrangement of the said disk plates being such that their contiguous faces shall be in contact, as shown.

Furthermore, it is practically necessary, in order to prevent the roller A binding from end-pressure against its journal, to introduce a disk-plate, K, capable of revolving freely, but with its hub abutting against the side of the frame, so as to furnish a fixed surface, to act in combination with the friction driving-disk plate D upon the disk B.

A further improvement consists in the employment of a clearer, to prevent thin articles from taking a wrong direction and winding around the lower roller.

It consists of a third roller, F, which may be of wood, in combination with the squeezing rollers.

In this instance the clearer is made to revolve by means of a cog-wheel upon the shaft of the roller C, whose motion is communicated to a cog-wheel on the axle of the clearer, through the pinion G, mounted on a stud-pin set in the frame.

This clearer, when the machine is in operation, revolves in its bearings H, in the same direction as the lower roller, whereby articles coming between the squeezing-rollers will be prevented from winding about the lower roller.

In place of the clearer described, a flat stationary guard may be used, whose lower edge is made concentric with the roller, and placed near to the surface of the same, so that the ends of articles, as they pass between the rollers, will fall naturally upon the top surface of the guard-plate, and be guided away from the lower roller.

What I claim as my invention, and desire to secure by Letters Patent, is—

1. Friction driving-plates B D K, in combination with rollers of vulcanized rubber or any other elastic compound impervious to water, for the purposes set forth.

2. A clearer, F, in combination with the squeezing-rollers of a washing and wringing-machine, geared as shown and described, for the purposes specified.

ELBRIDGE G. W. BARTLETT.
